UNITED STATES PATENT OFFICE

103,226

DESIGN FOR A SHOE

Jacob Fishman, Brooklyn, N. Y., assignor to Geo. E. Keith Company, Campello, Mass., a corporation of Massachusetts

Application December 28, 1936, Serial No. 66,772

Term of patent 3½ years

To all whom it may concern:

Be it known that I, Jacob Fishman, a citizen of the United States, residing at Brooklyn, in the county of Kings and State of New York, have invented a new, original, and ornamental Design for a Shoe, of which the following is a specification reference being had to the accompanying drawing, forming part thereof.

In the drawing:

Figure 1 is a top plan of a shoe showing my new design; and

Figure 2 is a side elevation of the same.

Both sides of the shoe present substantially the same appearance.

The essential feature of the invention resides in the arrangement and combination of curved lines of stitching and small and larger punched holes in the material of which the vamp and quarter are made. As the design is applicable to shoes of various shapes and styles the representation of shoe is merely conventional, for showing an application of the design.

I claim:

The ornamental design for a shoe, as shown and described.

JACOB FISHMAN.
